UNITED STATES PATENT OFFICE.

CARL B. EVANS AND SYLVANUS S. KNIERIM, OF WICHITA, KANSAS.

IGNITION-SPARK INTENSIFIER.

Application filed November 6, 1920. Serial No. 422,275.

To all whom it may concern:

Be it known that we, CARL B. EVANS and SYLVANUS S. KNIERIM, citizens of the United States, and both residents of Wichita, in the county of Sedgwick and State of Kansas, have invented certain new and useful Improvements in Ignition-Spark Intensifiers, of which the following is a specification.

Our invention relates to that class of ignition spark intensifiers in which the principal feature of the device is an insulated gap between two terminals which are spaced a fraction of an inch apart where designed for the ignition circuits of automobile engines or in fact of any internal-combustion engine.

Our invention provides a device of this kind, adapted to be made as a terminal for a distributor wire, at the spark-plug end of such wire. Our further object is to provide a device of the kind that may be cheaply manufactured and sold at a low price to owners of motor-cars.

It is a recognized fact that the performance of many automobile motors is improved by the use of this type of device in connection with ignition wiring. In addition to this advantage, these devices provide visible sparks for each cylinder of the motor, this visibility being a great convenience and time-saver when the operator wishes to test the strength and voltage of the ignition current.

Referring to the accompanying sheet of drawings:

35 Fig. 1 is a plan view of the preferred form of our device with the end of a distributor-wire attached; Fig. 2 is a side view of the same; Fig. 3 is an opposite plan view; Fig. 4 shows a modification.

40 In Figs. 1, 2 and 3, numeral 1 indicates a thin oblong piece of any suitable insulating material—preferably hard fibre. In one end of the piece a hole is punched and tapped. In this hole is placed a binding-screw 3. 45 A jam-nut 4 prevents the screw being jarred loose by the vibration of a motor car. Two other holes are punched in the piece 1 to receive a pair of tacks 5, 6, the heads of which are so spaced as to provide a spark-gap *a* of the desired length. The form of tack which we prefer is made with a large slightly convex brass head. The stem of tack 5 is upset or swaged at 5' to hold the tack permanently in position.

55 Copper rivets may be employed in lieu of tacks.

A sheet-metal terminal ear or "lug" 7 is formed with a pair of lateral flaps 7' which are folded around the base 1, one lapped over the other, and perforated for the tack 60 or rivet 6, which is swaged as shown at 6' thereby fastening the terminal part securely to the base 1.

The part 7 is provided with an opening, adapted to be passed over the top screw of 65 a spark-plug; for plugs having a removable terminal nut, a hole 9 is preferable. For plugs having an immovable top nut and an annular groove cut to receive a terminal, an open slot as 10' is necessary: however 70 such slot need not be straight, as shown, as it may be offset or pinched as a retaining means.

To put the device in use, one is provided for each cylinder of the motor. Connect 75 one to each distributor-wire (12) and attach the terminals to the respective spark-plugs.

By reference to Figs. 1 and 2 it will be observed that the head 5 adjacent the screw 3, is so located as to hold the loop of the 80 wire under the head of the screw. This is a feature of improvement and, we think, of novelty.

When the engine is running and the ignition functioning, there will be a visible 85 series of sparks between each pair of spark-gap heads, provided that the devices be shaded from too-bright sunlight when being inspected.

Having described our invention, what we 90 claim, and desire to secure by Letters Patent, is:

A sparking device comprising a thin, flat, oblong plate of insulating material, a sheet-metal spark-plug terminal, a headed member 95 6 passing thru said terminal and plate, a second headed member 5 passing thru said plate with its head spaced from the head of the first-mentioned headed member, a binding-screw threaded thru said plate in 100 close proximity to the last named headed member, and a jam-nut on said screw at the opposite side of the plate from the head of said screw, said member 5 serving as a retainer for the looped end of a conducting 105 wire, substantially as described.

CARL B. EVANS.
SYLVANUS S. KNIERIM.
